SIGN HOLDING DEVICE

Henry C. Pfaff, Jr., Newark, N. J.

Application August 31, 1933, Serial No. 687,567

7 Claims. (Cl. 40—145)

This invention relates to street sign display devices and more particularly to means for holding and supporting sign plates in such devices.

It is the common and general practice in most municipalities to provide at street intersections, devices showing the names of the streets. Such devices, being subjected to all kinds of weather and climatic conditions, must of necessity be durable; and they are generally made of metal. The name plates are loosely held in channelled frames. Heretofore, in the assembly of such devices it has been necessary to use a number of bolts and nuts. Such a type of structure requiring bolts and nuts in its assembly has been objectionable in that two or more workmen are required to assemble the device; and the bolts and nuts often become loosened and fall out.

Also, the bolts and nuts are often removed by mischievous boys of vandalistic tendencies, with the result that in many instances street intersections are not properly marked. Also, the baked or porcelain enamelled sign plates are frequently damaged by stresses caused by expansion and contraction of the metal frames in extremely hot or cold weather.

It is therefore an object of this invention to provide a street sign plate holding device which is formed in several parts properly spaced to allow for expansion and contraction of the metal under various climatic conditions.

A further object is the provision of a street sign plate holding device which requires no bolts and nuts in its assembly, so that the device can be readily and conveniently assembled by a single workman.

A further object is the provision of a single plate holding frame comprising two interchangeable parts of identical shape and simple structure, enabling the manufacture and assembly of sign holding devices at a low cost.

These and other advantageous objects which will later appear, are accomplished by the simple and practical construction and arrangement of parts hereinafter described and exhibited in the accompanying drawing, forming part hereof, and in which:

Fig. 1 is a plan view of the street sign holding device,

Fig. 2 is an elevational view of the device when used to indicate two intersecting streets,

Fig. 3 is an elevational view of the device taken at right angles to the view in Fig. 2,

Fig. 4 is a perspective view of the two-part sign plate holding frame used in the device,

Fig. 5 is a sectional view taken on line 5—5 of Fig. 2, and

Fig. 6 is a sectional view taken on line 6—6 of Fig. 3.

Referring to the drawing, in Fig. 4 is shown a sign plate holding frame comprising two U-shaped parts 8 and 9, identical in size and shape so that they can be readily interchanged. Each part has an internal channel 10 to loosely receive and support a sign plate 11, which generally is made of baked or porcelain enamel. Each part is substantially U-shaped and has on opposed sides semi-cylindrical bosses 12, 13, so that when the frame is assembled the bosses fit together to provide a cylindrical boss as shown in Fig. 3. An external rib 14, triangular in cross section as shown in Fig. 1, extends around the periphery of the frame.

Passing through the bosses 12, 13, is a rod 15, (Figs. 2, 3, 5) integral with a cylindrical cap 16, having opposed triangular grooves 17 adapted to fit over the rib 14 of the frame, the internal diameter of the cap 16 being slightly greater than the diameter of the cylindrical boss formed by the bosses 12, 13. The cap is usually provided with an integral ornament 26.

When, for example, two sign plates are used to designate two intersecting streets, the top rib 14 of the upper frame is engaged by the cap 16, while the bottom rib on the upper frame is engaged by opposed triangular grooves 19 in a collar 18, which surrounds the bosses on the lower side of the upper frame and on the upper side of the lower frame, (see Figs. 2, 3, 5) the collar 18 having grooves 19 to engage also the upper rib on the lower frame.

The lower rib 14 on the lower frame fits in grooves 22 in a collar 25 integral with a two-part cap 20 which fits over the top of and is clamped, by suitable means, to a cylindrical supporting post 21. The lower end of the rod 15 is threaded and passes through an aperture in cap 20.

In assembling the device, the cap 16 is fitted over the bosses 12, 13 of the upper frame, the rod 15 passing through the bosses and between the sign plates 11, which are bowed or spaced at the center to accommodate the rod 15. The collar 18 is then slipped over rod 15 and into position over the bosses on the under side of the upper frame. The lower frame members are then placed in position with the upper bosses 12, 13 thereon surrounded by cap 18. It should be here noted that the sign plates 11 are already in position in the frames.

The cap 20 is then positioned over the lower

bosses 12, 13 of the lower frame member, after which a nut 24 is threaded on the end 23 of rod 15 and rotated to draw the parts firmly together; upward movement of the nut 24 being prevented by the cap 20, so that rotation of the nut 24 draws the rod 15 downward to clamp the parts together. The cap 20 is then clamped onto the supporting post 21.

Obviously, when the device is used for a single sign plate, it is not necessary to use the collar 18.

The collar 18 is provided with a plurality of grooves 19 to enable the sign frames to be arranged at various angles to each other.

From the above description it will be seen that I have provided a sign holding device of simple structure requiring no nuts or bolts, and which can be readily assembled by a single unskilled workman. The parts are loosely fitted together so that allowance can be made for expansions and contractions due to changing weather.

The foregoing disclosure is to be regarded as descriptive and illustrative only, and not as restrictive or limitative of the invention, of which obviously an embodiment may be constructed including many modifications, without departing from the general scope herein indicated and denoted in the appended claims.

Having thus described my invention, what I claim as new and desire to secure by Letters Patent, is:

1. In a sign holding device, a frame member comprising a pair of substantially U-shaped internally channelled sections of identical size and shape, each of said sections having at the free ends of the legs thereof semi-cylindrical bosses, so that when the sections are assembled together said semi-cylindrical bosses cooperate to form cylindrical bosses, and means surrounding said bosses to hold the sections together, said sections having an external, peripheral rib of triangular cross-section.

2. In a sign holding device, a frame member comprising a pair of substantially U-shaped internally channelled sections of identical size and shape, each of said sections having at the free ends of the legs thereof semi-cylindrical bosses, so that when the sections are assembled together said semi-cylindrical bosses cooperate to form cylindrical bosses, and means surrounding said bosses to hold the sections together.

3. In a sign holding device, a frame member comprising a pair of substantially U-shaped internally channelled sections of identical size and shape, each of said sections having at the free ends of the legs thereof semi-cylindrical bosses, so that when the sections are assembled together said semi-cylindrical bosses cooperate to form cylindrical bosses, and cylindrical collars encompassing said bosses to hold the sections together.

4. In a sign holding device, a frame member comprising a pair of substantially U-shaped internally channelled sections of identical size and shape, each of said sections having at the free ends of the legs thereof semi-cylindrical bosses, so that when the sections are assembled together said semi-cylindrical bosses cooperate to form cy-

lindrical bosses, said sections having an external rib, and cylindrical collars encompassing said bosses to hold the sections together, said collars having grooves therein to cooperate with said ribs to maintain the collars in a definite position relative to the sections.

5. In a sign holding device, a pair of frame members for holding and supporting sign plates, each of said frame members having a pair of internally channelled sections of identical size and shape, each section being substantially U-shaped and having at the free ends of the legs thereof a semi-cylindrical boss, so that when the sections are assembled together said semi-cylindrical bosses cooperate to form cylindrical bosses, each section having an external rib of triangular cross-section, a rod passing through the bosses, said rod having, at its upper end, an integral cap which encompasses the upper cylindrical boss on the upper frame, a cylindrical collar encompassing the lower boss on the upper frame and the upper boss on the lower frame, a second cap having a collar encompassing the lower boss on the lower frame, said rod passing through the second cap and having a nut threaded on the end thereof, said second cap engaging the nut so that rotation of the nut on the rod will draw the rod downwardly to clamp the frame members together, and a supporting post to which said second cap is attached.

6. In a sign holding device, a pair of frame members for holding and supporting sign plates, each of said frame members having a pair of internally channelled sections of identical size and shape, each section being substantially U-shaped and having at the free ends of the legs thereof a semi-cylindrical boss, so that when the sections are assembled together said semi-cylindrical bosses cooperate to form cylindrical bosses, each section having an external rib of triangular cross-section, a rod passing through the bosses, said rod having at its upper end an integral cap which encompasses the upper cylindrical boss on the upper frame, a cylindrical collar encompassing the lower boss on the upper frame and the upper boss on the lower frame, a second cap having a collar encompassing the lower boss on the lower frame, said rod passing through the second cap and having a nut threaded on the end thereof, said second cap engaging the nut so that rotation of the nut on the rod will draw the rod downwardly to clamp the frame members together, and a supporting post to which said second cap is attached, said first-mentioned cap and said collars having grooves therein cooperating with said ribs to prevent rotation of the frame.

7. In a sign holding device, a frame comprising two interchangeable U-shaped internally channelled sections of identical size, each of the sections having at the free ends of the legs thereof a boss, collars surrounding said bosses to hold the sections together, and means associated with said collars and sections to prevent rotation of the collars relative to the sections.
